UNITED STATES PATENT OFFICE.

ANTHONY HOZLAK, OF NANTICOKE, PENNSYLVANIA.

GUN MOUNT.

Application filed March 11, 1926. Serial No. 93,935.

This invention relates to a gun mount and has for its object to provide, in a manner as hereinafter set forth, a mount of such class having means whereby the gun supported thereby can be angularly adjusted with respect to a vertical and a horizontal axis to train the same in position for firing.

Further objects of the invention are to provide, in a manner as hereinafter set forth, a gun mount which is simple in its construction and arrangement, strong, durable, conveniently adjusted to arrange the gun in the desired position for firing, thoroughly efficient in its use, and comparatively inexpensive to set up.

With the foregoing and other objects in view the invention consists of the novel construction, combination and arrangement of parts, as hereinafter more specifically described and illustrated in the accompanying drawings, wherein is shown an embodiment of the invention, but it is to be understood that changes, variations and modifications can be resorted to which fall within the scope of the claims hereunto appended.

In the drawings wherein like reference characters denote corresponding parts throughout the several views:

Figure 1 is a top plan view of a gun mount, in accordance with this invention, showing the adaptation therewith of the gun.

Figure 2 is a section on line 2—2 Figure 1.

Figure 3 is a section on line 3—3 Figure 1.

Referring to the drawings in detail 1 denotes a base upon which is mounted a turn-table 2 provided on its upper face with a circular gear rack 3. Suitable bearings 4 are interposed between the turn-table 2 and the base 1. The reference character 5 denotes a support on a deck of a vessel upon which the base 1 is secured. As illustrated the base 1 is arranged forwardly on the support or deck 5, of an observation room 6 and from the interior thereof the mount is adjusted to position the gun 7 at the desired angle with respect to a vertical and a horizontal axis whereby the gun will be properly trained for firing purposes.

The gun 7 is of a repeater type and formed with a pair of oppositely extending trun-

nions 8, 9 which are journaled in the upper end of an inverted U-shaped supporting frame 10 fixedly secured to the turn-table 2. Bearing members 11 are mounted at the upper end of the arms of the frame 10 for the trunnions 8 and 9. The trunnion 9 is provided with a gear wheel 12 which is arranged between one of the arms of the frame 10 and the gun 7. The gear 12 is positioned in proximity to one of the arms of the frame 10 and such arm is indicated at 13 and which has journaled therein below the gear wheel 12, a shaft 14, provided at its inner end with a pinion 15 which meshes with the gear 12. Stop collars 16 are carried by the shaft 14. The outer end of the shaft 14 is provided with a bevelled gear 17 spaced a substantial distance from the arm 13 of the frame 10 and secured to said arm 10 and extending outwardly therefrom is a bearing bracket 18 for the shaft 14. Secured to the arm 13, of the frame 10, below the bearing bracket 18, is a superposed spaced pair of bearing brackets 19 and 20.

Extending upwardly through the outer ends of the brackets 19 and 20 is a vertically disposed shaft 21, provided at its upper end with a bevelled gear 22, which meshes with the bevelled gear 17. The hub 23 of the gear 22 seats upon the top of the bracket 19, which is arranged in proximity to the bracket 18. The lower end of the shaft 21, below the bracket 20 is provided with a pinion 24, having its hub 25 abutting against the lower face of the bracket 20. The hubs 23 and 25 prevent vertical movement of the shaft 21 relative to the brackets 19 and 20.

Secured to the outer face of the arm 13, of the frame 10, below the bracket 20, is a pair of outwardly projecting and oppositely inclined suspension arms 26, 27 for slidably supporting a shiftable actuating member referred to generally by the reference character 28. The member 28 consists of a segmental shaped bar 29 provided on its bottom with a toothed rack 30 and on its inner edge with a toothed rack 31. The pinion 24 meshes with the rack 31 whereby when the member 28 is bodily shifted in either direction the shaft 21 will be revolved, and which will revolve the shaft 14, owing to the gear

connections 17 and 22. When the shaft 14 is revolved, the pinion 15 is carried therewith, and as the latter meshes with the gear 12 the trunnion 9 will be shifted for the purpose of 5 adjusting the gun 7 in an angular direction with respect to its horizontal axis. The turn-table 2 is revolved for the purpose of angularly adjusting the gun 7 with respect to its vertical axis, by a bevelled gear 32 10 which meshes with the bevelled rack 3 formed on the turn-table 2. Journaled in a pair of supporting standards 33 is a driven shaft 34, and which has its outer end provided with a bevelled pinion 35. Bodily 15 shiftable upon the shaft 34, that is to say lengthwise of the latter, as well as adapted to revolve therewith when clutched with the shaft 34, is the bevelled gear 32 and a gear wheel 36. The gears 32 and 36 are carried 20 by a clutching mechanism 37, operated by a shifting mechanism 38 therefor, which is pivotally mounted on the standards 39 and 40 and extends into the observation room 6 so that said shifting mechanism can be operated 25 from such room and when operated in one direction coupling the gear wheel 32 with the shaft 34 and further shifting the gear wheel 32 to engage with the rack 3 so that when the shaft 34 is operated the turn-table 2 will be revolved. When the shifting mechanism 38 is operated in the other direction the gear wheel 36 is moved to mesh with the rack 30 of the member 28 and on the 30 operation of the shaft 34 the gear wheel 36 meshing with the rack 30 will shift the element 28 and on the shift of the latter the rack 31 engaging with the pinion 24 will 35 operate the shaft 21. The suspension arms 26 and 27 have their outer end formed to support and to provide for the shifting of the element 28 therethrough. Any suitable 40 means can be employed to prevent the back rotation of the turn-table 2, and such means is indicated at 41 and can consist of a dog shiftable to engage the rack 3 to prevent 45 back rotation thereof.

A spring controlled shell feed and ejector mechanism of any suitable construction 50 forms an element of the gun 7 and which includes a water tight spring controlled operating lever 42 operated by a flexible cable 43 extending through a guide 44 carried by the turn-table 2 and which winds on and off the bottom of a drum 45 mounted in the brackets 46. The spring controlled shell feed and ejector mechanism is of a 55 type to alternately position a shell for firing and for ejecting the shell after being fired.

The drum 45 is revolved from the interior of 60 the observation room 6, and for such purpose one end of the shaft of the drum 45 is provided with a bevelled pinion 47, which meshes with a bevelled pinion 48 carried by the shaft 49, which extends into the room 65 6, and carries an operating handle 50.

A spring controlled firing mechanism forms an element of the gun and which includes a spring controlled operating lever 51 operated by a flexible member 52 extending through the guide 44 and through and into the wall of the observation room 6. A spring controlled firing pin is indicated at 52'. The controlling springs for the levers 42 and 51 are indicated at 42' and 51' respectively. 75

The shaft 34 is driven through the medium of an operating shaft 53, which is mounted in standards 54, 55 secured to the support or deck 5. The shaft 53 is disposed at right angles with respect to the shaft 34 80 and has its outer end provided with a bevelled pinion 56, which meshes with the bevelled pinion 35 formed on the outer end of the shaft 34. The shaft 53 extends into the observation room 6 and carries an operating handle 57 therefor. It will be said that any suitable means can be employed to operate the shaft 53, and this statement also applies to the shaft 49. It will be furthermore stated that the clutch mechanism and its shifting means therefor can be of any suitable arrangement. 85

It is thought the many advantages of a gun mount, in accordance with this invention, can be readily understood in view of the fact that the gun can be conveniently adjusted to various inclinations with respect to a horizontal axis and also to various inclinations with respect to a vertical axis, and although the preferred embodiment of the invention is as illustrated and described, yet it is to be understood that changes in the details of construction can be had which will fall within the scope of the invention 90 as claimed. 100

What I claim is:—

1. A gun mount comprising a turn-table, a frame bodily shiftable therewith and pivotally supporting the trunnions of the gun, a gear wheel carried by one of the gun trunnions, a bodily shiftable actuating member provided with a pair of racks disposed at an angle to each other, means secured to said frame for slidably supporting said member, means for shifting said turn-table to adjust the gun on a vertical axis, means engaging with one of said racks for shifting said member, means carried by the frame and engaging with said gear and operated from the other rack of said member for adjusting the gun on a horizontal axis, and a common operating means for the means for shifting said member and the means for shifting the turn-table. 110

2. A gun mount comprising a frame for pivotally supporting the trunnions of a gun, a gear wheel fixed to one of the gun trunnions, a bodily shiftable segment-shaped actuating member provided with a pair of 115 racks disposed at an angle to each other, 120

revoluble means carried by the frame and engaging with said gear for shifting the same to adjust the gun on a horizontal axis, revoluble vertically disposed means supported by the frame for operating the first mentioned means and having a pinion meshing with one of said racks to provide for the operation thereof when said member is bodily shifted, and revoluble means engaging with the other of said racks for bodily shifting said member. 10

In testimony whereof, I affix my signature hereto.

ANTHONY HOZLAK.
